 Raytheon Manufacturing Company, Newton,
 Mass., a corporation of Delaware

Application January 9, 1940, Serial No. 313,078

16 Claims. (Cl. 172—281)

This invention relates to inverters of the type in which direct current or low frequency alternating current is converted into alternating current of a relatively higher frequency by means 5 of controlled gas or vapor-filled electrical discharge tubes.

An object of this invention is to increase the efficiency and reliability of operation of such inverters.

10 Another object is to increase the permissible output frequency to such an extent that said frequency is greater than the rate at which the tubes can deionize.

Another object is to increase the power output 15 obtainable with a given number of such discharge tubes.

A further object is to increase the deionization time available wherein each of such tubes may 20 become completely deionized before a voltage tending to make them conductive is again applied thereto.

A further object is to decrease the rate at 25 which the voltage on each of the discharge tubes increases at the end of the deionization time, thus eliminating any tendency for the tubes to fire prematurely.

30 A still further object is to fix the output frequency of the system by the circuit constants rather than by the rate at which the tubes are fired.

The foregoing and other objects of my invention will be best understood from the following description of exemplifications thereof, reference 35 being had to the accompanying drawings, wherein:

Fig. 1 is a diagram of one embodiment of my invention;

Fig. 2 contains a set of curves illustrating the 40 mode of operation of the system as shown in Fig. 1;

Fig. 3 is a diagram of another embodiment of my invention;

Fig. 4 contains a set of curves illustrating the 45 mode of operation of Fig. 3;

Fig. 5 is a diagram of a still further embodiment of my invention in which a plurality of condenser and discharge tubes are utilized; and

Fig. 6 contains curves pertaining to the operation 50 of the arrangement as shown in Fig. 5.

In Fig. 1 direct current or relatively low frequency alternating current is adapted to be connected to input terminals 1 and 2. The system illustrated converts the input current to relatively higher frequency alternating current which is supplied to an alternating current output device

3. Since such a circuit usually contains both inductance and resistance, it may be represented as in Fig. 1 diagrammatically by an inductance and a resistance. A condenser 4 is charged with current from the input terminals 1 and 2 through 5 an impedance 5 which is preferably an inductance. The value of this impedance is so chosen as to maintain the proper charging rate of the condenser 4. During actual operation of the device, the impedance 5 tends to keep the current 10 flowing therethrough at a substantially constant value. The charge on the condenser is adapted to be discharged into the output device 3 through a controlled ignition discharge tube 6. This tube is preferably of the pool cathode type with 15 an igniter for initiating a cathode spot on the pool in order to cause the tube to conduct current. Although any suitable type of igniter may be used, it preferably is of the type described and claimed in the copending application of Percy 20 L. Spencer, Serial No. 303,963, filed November 13, 1939, for an improvement in Arc igniting devices, consisting of a conductor separated and insulated from the cathode by a thin glass layer. The tube 6 is provided with an anode 7 connected to the 25 positive side of the condenser 4 in the case where the input to the condenser is direct current. The tube 6 is likewise provided with a cathode 8, preferably of mercury, connected to one side of the output device 3. The other side of said output device is connected to the negative side of the condenser 4. The tube 6 is provided with an igniter 9, preferably of the type as described above. This igniter is adapted to be supplied with igniting impulses from the secondary winding 10 of an ignition transformer 11 having a primary winding 12. This primary winding is supplied with periodic peaked voltage impulses from any suitable source for igniting the tube 6. For example, the source may consist of a series 30 type inverter, such as is illustrated in Fig. 1. This inverter comprises two controlled ignition discharge tubes 13 and 14, and a pair of condensers 15 and 16. Direct current to be inverted is supplied to terminals 17 and 18. The positive 35 side of condenser 15 is connected directly to the positive terminal 17 while the negative side of the condenser 16 is connected directly to the terminal 18. The negative side of the condenser 15 is connected to the positive side of the condenser 16. The tube 13 is provided with an anode 19 connected to the positive terminal 17 while the tube 14 is provided with a cathode 20 connected to the negative terminal 18. The cathode 20 is preferably of the permanently- 40

55

energized type, as for example a thermionic filament. The tube 13 also is provided with a cathode 21, preferably of the permanently-energized type, such as a thermionic filament which is connected to one side of the primary winding 12. The other side of said primary winding is connected to the point between the condensers 15 and 16 through an adjustable energy-consuming resistance 28. The tube 14 is provided with an anode 22 connected to one side of a primary winding 23 of a transformer 24. The other side of the primary winding 23 is likewise connected through resistance 26 to the point between the condensers 15 and 16. The transformer 24 is provided with a short-circuited secondary winding 25. Although the voltage impulses supplied to the transformer 24 are not utilized in Fig. 1, they are available for ignition of another tube if more than one tube, such as 6, is provided. The tubes 13 and 14, which are preferably of the gas or vapor-filled type, are provided with control electrodes, such as grids 27 and 28, respectively. These grids are normally biased so as to prevent the tubes 13 and 14 from firing by means of biasing batteries 29 and 30, respectively. Firing impulses are superimposed on these biasing potentials between the anodes and cathodes of tubes 13 and 14 from secondary windings 31 and 32 of a transformer 33 which is fed with alternating current of a suitable frequency from any suitable source of alternating current, such as a vacuum tube oscillator 34. This vacuum tube oscillator may be of adjustable frequency. One side of the secondary winding 31 is connected through the battery 29 to the grid 27, while the other side of said secondary winding 31 is connected directly to the cathode 21. One side of the secondary winding 32 is connected through the battery 30 to the grid 28. The other side of said secondary winding 32 is connected directly to the cathode 20. Due to the firing impulses supplied from the oscillator 34, the grids 27 and 28 alternately render the tubes 13 and 14 conductive. As this action occurs, periodic peaked voltages of opposite polarity appear across the secondary windings 10 and 25. As indicated above, the voltages appearing across the secondary winding 25 are not utilized. The voltage impulses appearing across the winding 10 are impressed upon the igniter 9, and thus cause the tube 6 to be fired upon each such igniting impulse being supplied thereto.

An auxiliary rectifier tube 35 is connected directly across the tube 6. This rectifier tube is preferably of the permanently-energized cathode type, and therefore is provided with a cathode 36 which may be, for example, a thermionic filament. This cathode 36 is connected to the anode 1. The tube 35 also has an anode 37 connected directly to the cathode 8.

The operation of the system illustrated in Fig. 1 may be more clearly understood by referring to the curves of Fig. 2. Along axis *a* E_c represents the voltage appearing across condenser 4 while *I* represents the current supplied from said condenser to the output device 3. On axis *b*, E_t represents the voltage across the tubes 6 and 35. These curves do not purport to show quantitatively what happens in the system illustrated in Fig. 1, but they do represent the operation qualitatively. The charging current supplied to the condenser 4 gradually raises its voltage E_c until it rises to a predetermined value at the time T_1 . Thereupon an igniting impulse is supplied to the igniter 9, causing the tube 6 to be-

come conductive. The condenser 4 then discharges through said tube 6 into the output device 3, delivering a pulse of current *I* which rises to a maximum, at which time the voltage E_c falls to zero. Due to the inductance of the output device 3, the current *I* continues to flow in the same direction but decreases in magnitude until it reaches zero at the time T_2 . During this period, the condenser 4 charges up in the opposite direction. At T_2 the voltage E_c built up across the condenser 4 tends to cause the current *I* to reverse. This reverse current cannot flow through the tube 6 inasmuch as it is a rectifier. However, tube 35 which is connected in opposite polarity to that of tube 6, provides a path for this reverse current, and therefore a pulse of reverse current flows during the time between T_2 and T_3 . During this period, the voltage E_c again passes through zero, and rises to a positive value at the time T_3 . When the current *I* tends to reverse at the time T_3 , the tube 6 which was extinguished at the time T_2 is no longer conductive, and therefore cannot further conduct any current. Also the polarity of the tube 35 is such as to oppose such flow. The value to which the voltage E_c rises at the time T_3 depends upon the degree to which energy has been absorbed during the time T_1-T_3 in the output device 3. The greater the degree of energy absorption, the lower will be this final value of E_c . Actually it may be very much smaller than the initial value to which the condenser 4 was charged, and ordinarily is so low that it cannot cause the tube 6 to become conductive in absence of a positive firing impulse supplied to the igniter 9. Thus substantially all the energy which was not absorbed in the output device 3 during the period T_1-T_3 is restored to the condenser 4 in the proper polarity so as to again be available to be dissipated into the output device 3 upon the next ignition of the tube 6. Due to the conservation of this energy, the system operates very efficiently with a minimum of energy loss. After T_3 , current from the input terminals 1 and 2 flows to the condenser 4 to again charge said condenser to the desired voltage. Therefore, during the period T_3-T_4 , the voltage E_c rises gradually to the full value when the igniter 9 again fires the tube 6, and the operation described is repeated.

Between T_2 and T_3 the voltage across the tube 6 is only the relatively small voltage drop across the tube 35, and furthermore is in the non-conducting direction on said tube 6. Therefore, during the period T_2-T_3 , the tube 6 has no tendency to pass current and has an opportunity to deionize. At the time T_3 , E_t across the tube 6 again reverses, and is impressed upon the tube 6 in the conducting direction. However, as pointed out above, the value E_t at the time T_3 is ordinarily insufficient to cause any tendency for the tube 6 to fire. If at this time the tube 6 has not become completely deionized and any tendency to fire exists, no harm is done because the operation, as indicated by the dotted lines in Fig. 2, occurs. If reignition of the tube 6 occurs at the point T_3 , a succeeding pulse of current I_1 , as represented by the dotted lines, will be supplied to the output device 3. The voltage will follow the dotted curve E_{c1} , and at the end of this second current alternation will rise to a smaller positive value than at the time T_3 . This latter positive value of the voltage across the tube 6 being still less than the value occurring at T_3 has still less tendency to cause the tube 6 to fire. The voltage E_{c1} will then rise along the dotted

curve to a certain value at T_4 when the igniter 9 refires the tube 6. It will be seen that re-ignition of the tube 6 at T_5 simply results in an added pulse of current being supplied to the load and the voltage on the condenser 4 on the next firing being somewhat reduced. Also additional reignitions of the tube 6 following the time T_3 could occur without disadvantageous results. As for the tube 35, no problem of deionization time exists therein inasmuch as that tube is intended to fire each time its anode becomes positive.

From the analysis as given in Fig. 2, it will be seen that the frequency of the current supplied to the output device 3 is controlled by the circuit constants, including the value of the capacity 4 and of the inductance and resistance of the output device 3, and not by the frequency at which the tube 6 is fired. The frequency of the output current can be made considerably greater than that determined by the time during which the tube 6 can deionize. As pointed out above, a tube with a relatively long deionization time might supply a train of current pulsations each time it is fired without any deleterious effects in so far as the operation of the system is concerned. Therefore, an inverter built in accordance with the present invention no-longer is limited by deionization time of the tubes which heretofore has constituted a serious limitation of the frequency which such inverters have been able to furnish.

The effect of varying the frequency at which the tube 6 is fired is to vary the number of high frequency current pulsations supplied per unit of time. The greater the rate at which these pulsations are supplied, the greater will be the power supplied to the output device, and conversely. Thus by varying the frequency of the oscillator 35 40 34, the power which is supplied to the output device 3 can be varied.

As pointed out in connection with Fig. 1, each ignition of the tube may supply a train of current alternations to the output device. In some instances it may be desirable to devise a system in which the production of a train of current alternations is insured for each ignition of the tube. Such an arrangement is shown in Fig. 3. In this figure the same reference numerals are applied where the elements are identical with those shown in Fig. 1. The tube 6 in this modification is provided with an auxiliary holding anode 38, which is connected through a resistance 39 and a condenser 40 to the cathode 3. The condenser 40 is adapted to be charged to a predetermined potential from a suitable source of direct current, such as a battery 41, and a current-limiting resistance 42 which determines the proper charging rate for the condenser 40.

60 The operation of the system shown in Fig. 3 will be better understood by a reference to Fig. 4. In this figure, on axis *a*, E_c again represents the voltage on condenser 4, while *I* represents the current supplied to the output device 3. On axis 65 *b*, E_h represents the voltage across the condenser 40. As in the case of Fig. 1, the charging current to the condenser 4 raises its voltage to a predetermined value, and at the time T_1 the igniter 9 is supplied with an igniting impulse which fires the tube 6. The voltage on the condenser 4 then causes a discharge current to pass through the tube 6 into the output device 3. At the time T_1 likewise the voltage E_h has risen to a predetermined value, due to the charging current flowing 70 to the condenser 40 from the battery 41. When 75

the tube 6 is ignited, a discharge current flows from the condenser 40 through the resistance 39 and anode 38 to an arc spot established on the cathode 8. The resistance 39 is of a value to give a relatively long time constant to the discharge circuit of condenser 40, so that the voltage E_h falls off, as shown between T_1 and T_2 in Fig. 4. Throughout this time a holding arc is maintained between the cathode 8 and the anode 38, so that a discharge may pass to the anode 7 each time it becomes positive throughout this period. Therefore the current pulsations from the discharge circuit of condenser 4 which tend to flow in one direction pass through the tube 6 from the anode 7. The current which tends to flow in the opposite direction passes through the tube 35 from the anode 37. As a result, a train of current alternations I of decreasing amplitude is supplied to the output device 3, and the voltage E_c across the condenser 4 likewise is alternated with decreasing amplitude. At T_2 the voltage and consequently the current flowing from the anode 38 falls to such a value that it is incapable of maintaining an arc to the cathode 8, whereupon said arc is extinguished. If at this time current is still flowing from the anode 7, such current will continue to flow until it has fallen substantially to zero, whereupon the tube 35 will cause an additional pulse of current to flow in the opposite direction, and then cease, as explained in connection with Figs. 1 and 2. The voltage E_c on the condenser 4 at the time of the extinction of the tube 35 again has a positive value which represents any energy which has not been absorbed in the output circuit. However, due to the fact that the output circuit has been supplied with a train of current alternations, the energy absorption is considerable, and therefore the final value of E_c is very low, entirely eliminating any further tendency for the tube 6 to fire. Here again an additional ignition of the tube 6 does no harm, merely resulting in an additional alternation of current supplied to the output circuit. Voltage E_c again rises to its maximum value, due to the charging current flowing thereto, and at the time T_3 the igniter 9 again ignites the tube 6 and the sequence of operations is repeated. During the time T_2-T_3 , the condenser 40 likewise recharges from the battery 41, and the voltage E_h rises, as indicated in Fig. 4, to its maximum value so as to be available for establishing a holding arc as explained above.

In the case of Figs. 3 and 4, the frequency again is determined by the circuit constants rather than by the frequency at which the tube 6 is ignited. 55 Here again the output frequency can be much greater than the speed with which the tube 6 can be deionized, so that the system can supply high frequency current with extreme reliability.

As mentioned in connection with Fig. 1, additional ignition tubes may be utilized for supplying current pulsations to the output. As a matter of fact, any number of such tubes together with associated condensers may be combined in a single system whereby the power output obtainable is multiplied. Such an arrangement is shown, for example, in Fig. 5. In this figure direct current or relatively low frequency alternating current is adapted to be connected to the input terminals 43 and 44 and alternating current supplied to an output device 45 similar to the output device 3 of Fig. 1. A plurality of condensers, for example three in number, 46, 47 and 48, are provided which are charged through impedances 49, 50 and 51, respectively connected 70 75

between the input terminal 44 and said condensers.

One side of each of said condensers, which may be the positive side in the case of a direct current supply, are connected to the input terminal 43. The condensers 46, 47 and 48 are adapted to be discharged into the output device 45 through controlled ignition discharge tubes 52, 53 and 54. These tubes are preferably of the same type as tube 6 described in connection with the previous figures. These tubes are provided with pool cathodes 55, 56 and 57 connected respectively to the negative sides of the condensers 46, 47 and 48. These controlled ignition tubes likewise are provided with anodes 58, 59 and 60, respectively, which are connected together through the output device 45 to the terminal 43. The tubes 52, 53 and 54 are likewise provided with igniters 61, 62 and 63, respectively. These igniters are adapted to be supplied with igniting impulses from secondary windings 64, 65 and 66 of ignition transformers 67, 68 and 69, respectively, whose primary windings 70, 71 and 72 are adapted to be supplied in sequence with igniting impulses from any suitable source. As illustrated in Fig. 5, these igniting impulses are supplied to said primary windings from a supply transformer 76 having secondary windings 73, 74 and 75 connected in star. The outer ends of said secondary windings 30 are connected in series with the primary windings 70, 71 and 72 whose outer ends are grounded. Said supply transformer secondary is likewise provided with a grounded neutral 79. The transformer 76 is provided with a primary winding 77 connected for example in delta and supplied with a three-phase voltage from a suitable three-phase oscillator 78. This oscillator is preferably of the type which supplies peaked voltage waves to each of the three phases of the transformer. In this 40 way the secondary windings 64, 65 and 66 are supplied in sequence with peaked igniting impulses which cause the tubes 52, 53 and 54 to be ignited in sequence. These tubes are ordinarily constituted so that a tendency for an arc spot 45 to form on their associated cathodes occurs only when the igniter is made positive with respect to its associated cathode, and therefore these tubes will ordinarily fire only on the positive voltage peaks supplied by the transformer 76.

50 In order to provide a path for the negative pulses of current which cannot flow through the tubes 52, 53 and 54, as explained in connection with the previous embodiments, an auxiliary discharge tube 80 is provided. This tube contains 55 a cathode of the permanently-energized type which may be, for example, a pool of mercury to which a holding arc is maintained by means of auxiliary holding anodes. Thus tube 80 contains such a pool cathode 81 and a pair of auxiliary holding anodes 82. These anodes are connected to opposite sides of the secondary winding 83 of a holding transformer 84 whose primary winding 85 is adapted to be supplied from a suitable source of alternating current. The secondary winding 83 is provided with a center tap 86 connected through an inductance 87 to the cathode 81. An arc spot is established on the cathode 81 by any suitable igniting means which may be, for example, an igniter of the type as indicated 60 in connection with tubes 52, 53 and 54. Thereupon current flows alternately from the two anodes 82 to the arc spot on the cathode. These currents overlap, due to the inductance 87, so that the cathode spot is permanently maintained.

65 70 75 The constants of the transformer 84 and the

associated circuit are so chosen that a reasonable value of current flows from the anodes 82.

The cathode 81 is connected directly to the common lead extending to the anodes of the tubes 52, 53 and 54. The tube 80 is likewise provided with three anodes 88, 89 and 90 connected respectively to the cathodes 55, 56 and 57.

When the system described above is energized, the condensers 46, 47 and 48 each acquire a charge from the input terminals 43 and 44. One of the 10 tubes, for example 52, is ignited by an ignition impulse being supplied to the igniter 61. Thereupon the condenser 46 discharges through said tube 52 into the output device 45. When the discharge current flowing from the condenser 15 46 tends to reverse, as explained in connection with the previous embodiments, such reverse current can flow from the anode 88 to its associated cathode 81. Thus the operation of the condenser 42, the tube 52, and the anode 88 of tube 80 operates exactly as explained in connection with the operation of the single pair of tubes of Figs. 1 and 3. Following the sequence of operations established by igniting the tube 52, the tubes 53 and 54 are ignited in sequence. Each such ignition produces a similar sequence of operations, each resulting in furnishing the output device 45 with one or more alternations of high frequency current. As indicated in Fig. 6, the output current supplied by igniting the tubes 52, 53 and 54 are combined in the output device 45. Thus, for example, I_a represents the current supplied from condenser 46 and tube 52; I_b , the current from condenser 47 and tube 53; and I_c , the current from condenser 48 and tube 54. Each of 35 these currents follow one another in sequence in the output device 45, and therefore although each of the tubes 52, 53 and 54 are fired at a certain frequency, the number of current pulsations supplied to the output device 45 is the sum 40 of the current pulsations supplied from these tubes.

As explained in connection with the previous embodiments, the frequency of the output current is determined by the circuit constants rather than by the rate at which the tubes are fired. Also the power which is supplied to the output device is determined by the number of current pulsations supplied per unit of time. By utilizing a plurality of such tubes, as indicated in Fig. 50 5, a greater number of such current pulsations per unit of time can be supplied to the output device, and therefore this embodiment represents an arrangement for increasing the power output 55 of the inverting system.

Of course it is to be understood that this invention is not limited to the particular details as described above as many equivalents will suggest themselves to those skilled in the art. In the case where alternating current is impressed upon 60 the input terminals, it will be understood that the system will operate upon the positive half of each current cycle. Also systems may be devised which would utilize both halves of such an impressed alternating current wave. Also other 65 types of tubes and control devices could be utilized. Various other modifications and ideas as to the utilization of the principles enunciated herein will suggest themselves to those skilled in the art. It is accordingly desired that the appended claims be given a broad interpretation 70 commensurate with the scope of the invention within this art.

What is claimed is:

1. An inverter comprising condenser means, 75

means for charging said condenser means, an alternating current output circuit, space discharge means for discharging said condenser means into said output circuit by an oscillating discharge whose frequency is determined by the condenser means and its associated discharge circuit and for limiting the number of current oscillations in said discharge to a predetermined number, and means for initiating the discharge operation of said space discharge means at a predetermined frequency.

2. An inverter comprising condenser means, means for charging said condenser means, an alternating current output circuit, space discharge means for discharging said condenser means into said output circuit by an oscillating discharge whose frequency is determined by the condenser means and its associated discharge circuit and for limiting the number of current oscillations in said discharge to a predetermined number, and means for initiating the discharge operation of said space discharge means at a predetermined frequency which is less than said oscillating frequency.

25 3. An inverter comprising condenser means, means for charging said condenser means, an alternating current output circuit, ionizable gas or vapor-filled space discharge means for discharging said condenser means into said output circuit by an oscillating discharge whose frequency is determined by the condenser means and its associated discharge circuit and for limiting the number of current oscillations in said discharge to a predetermined number, said oscillating frequency being greater than that determined by the deionization time of said space discharge means, and means for initiating the discharge operation of said space discharge means at a predetermined frequency which is less than

40 said oscillating frequency.

4. An inverter comprising condenser means, means for charging said condenser means, an alternating current output circuit, controlled ignition rectifying space discharge means for discharging said condenser means into said output circuit by an oscillating discharge, rectifying means of opposite polarity to said space discharge means connected to provide a path for the negative part of said oscillating discharge, and means for igniting said space discharge means at a predetermined frequency.

5. An inverter comprising condenser means, means for charging said condenser means, an alternating current output circuit, controlled ignition rectifying space discharge means for discharging said condenser means into said output circuit by an oscillating discharge, rectifying means of opposite polarity to said space discharge means connected across said space discharge means, and means for igniting said space discharge means at a predetermined frequency.

6. An inverter comprising condenser means, means for charging said condenser means, an alternating current output circuit, pool cathode type rectifying space discharge means for discharging said condenser means into said output circuit by an oscillating discharge, rectifying means of opposite polarity to said space discharge means connected across said space discharge means, and means for initiating arc spots on said cathode at a predetermined frequency.

7. An inverter comprising condenser means, means for charging said condenser means, an alternating current output circuit, a discharge tube having a pool type arcing cathode and an

anode connected in series with said condenser means and said output circuit, a rectifying tube having a permanently-energized type of cathode connected to said anode, and an anode connected to said pool type cathode, and means for initiating arc spots on said pool type cathode at a predetermined frequency.

8. An inverter comprising condenser means, means for charging said condenser means, an alternating current output circuit, space discharge means for discharging said condenser means into said output circuit by an oscillating discharge, said discharge means comprising a discharge tube having a pool type arcing cathode and an anode connected in series with said condenser means and said output circuit, rectifying means of opposite polarity to said space discharge means connected across said space discharge means, means for establishing a holding arc to said pool type cathode for a plurality of the periods of said oscillating discharge, and means for initiating arc spots on said pool type cathode at a predetermined frequency.

9. An inverter comprising condenser means, means for charging said condenser means, an alternating current output circuit, controlled ignition rectifying space discharge means for discharging said condenser means into said output circuit by an oscillating discharge, rectifying means of opposite polarity to said space discharge means connected across said space discharge means, and means for igniting said space discharge means at a predetermined frequency and for maintaining said space discharge means ignited for a plurality of the periods of said oscillating discharge.

10. An inverter comprising a plurality of condenser means, means for charging said condenser means, an alternating current output circuit, a plurality of space discharge means for discharging said condenser means in sequence into said output circuit by an oscillating discharge whose frequency is determined by each condenser means and its associated discharge circuit and for limiting the number of current oscillations in said discharge to a predetermined number, and means for initiating the discharge operation of each of said space discharge means in sequence at a predetermined frequency.

11. An inverter comprising a plurality of condenser means, means for charging said condenser means, an alternating current output circuit, a plurality of space discharge means for discharging said condenser means in sequence into said output circuit by an oscillating discharge, and means for initiating the discharge operation of each of said space discharge means in sequence at a predetermined frequency which is less than said oscillating frequency.

12. An inverter comprising a plurality of condenser means, means for charging said condenser means, an alternating current output circuit, a plurality of ionizable gas or vapor-filled space discharge means for discharging said condenser means into said output circuit by an oscillating discharge whose frequency is determined by the condenser means and its associated discharge circuit and for limiting the number of current oscillations in said discharge to a predetermined number, said oscillating frequency being greater than that determined by the deionization time of said space discharge means, and means for initiating the discharge operation of each of said space discharge means in sequence at a predetermined frequency.

mined frequency which is less than said oscillating frequency.

13. An inverter comprising a plurality of condenser means, means for charging said condenser means, an alternating current output circuit, a plurality of controlled ignition rectifying space discharge means for discharging said condenser means into said output circuit by an oscillating discharge, rectifying means of opposite polarity to said space discharge means connected across each of said space discharge means, and means for igniting each of said space discharge means in sequence at a predetermined frequency.
14. An inverter comprising a plurality of condenser means, means for charging said condenser means, an alternating current output circuit, a plurality of pool cathode type rectifying space discharge means for discharging said condenser means into said output circuit by an oscillating discharge, rectifying means of opposite polarity to said space discharge means connected across each of said space discharge means, and means for initiating arc spots on each of said pool type cathodes at a predetermined frequency.

25

15. An inverter comprising condenser means, means for charging said condenser means, an alternating current output circuit, a discharge tube having a cathode and an anode connected in series with said condenser means and said output circuit, a rectifying tube having a permanently-energized type of cathode connected to said anode, and an anode connected to said first-named cathode, and means for firing said discharge tube at a predetermined frequency. 10

16. An inverter comprising a plurality of condenser means, means for charging said condenser means, an alternating current output circuit, a plurality of discharge tubes each having a cathode and an anode connected in series with each of said condenser means and said output circuit, a rectifying tube having a permanently-energized type of cathode connected to all of said anodes, and a plurality of anodes connected to each of said first-named cathodes, and means for firing said discharge tubes in sequence at a predetermined frequency. 15 20
